(57) **CLAIM**

The ornamental design for case for handheld electronic
device, as shown and described.

DESCRIPTION

(62) Division of application No. 29/358,510, filed on Mar.
29, 2010, now Pat. No. Des. 654,068.

FIG. 1 is a front perspective view of a novel front plate of a
case for handheld electronic device.

(51) **LOC (9) Cl.** **14-03**

FIG. 2 is a rear perspective view of a novel rear plate for the
case and cover of FIG. 1.

(52) **U.S. Cl.** **D14/250**

FIG. 3 is a front view of a case and cover of the front and rear
plates of FIG. 1 and FIG. 2.

(58) **Field of Classification Search** D14/250,
D14/252, 253, 248, 249, 440, 203.7, 217,
D14/203.3, 203.4; D3/201, 218, 269; 220/4.02;
224/191, 241, 245; 379/426, 433.01; 455/575.1,
455/575.8

FIG. 4 is a rear view of the case and cover with the case shown
with ear phones inside the compartment of FIG. 3.

See application file for complete search history.
